CASE MOUNTING

Samuel L. Beber, Los Angeles, Calif.

Application August 20, 1951, Serial No. 242,677

11 Claims. (Cl. 220—3.6)

1

This invention has to do with a case mounting and is more specifically concerned with a structure applicable to a typical wall, and it is a general object of the invention to provide a structure serving to effectively and securely mount a case, housing, or other like element, in or on a wall.

In the usual building, whether dwelling or for commercial use, it is common to employ walls having facings of lath and plaster, and this type of construction is such that it ordinarily requires that casings, housing, or like parts of accessories to be mounted on or in such walls, must be incorporated during construction, as otherwise serious difficulties and complications are likely to be encountered. Cases or housings of the type referred to may be parts of cabinets of various kinds, or for various purposes, may be the bodies or shells of lighting fixtures, etc., and, in practice, such elements are usually formed of sheet metal.

The structure provided by the present invention is in most cases applied to what may be termed the facing of a wall, which element of a building is ordinarily formed of lath or plasterboard and plaster carried thereon. The term "facing" as hereinafter used is intended to include not only lath or wallboard and plaster, but any other like or similar structure or combination of elements. Furthermore, the term "wall" when applied to or used in connection with part of a building is intended to include not only the vertical walls or partitions occurring in such building, but also is intended to include ceilings and other such elements of construction.

It is a general object of this invention to provide a case mounting applicable to a wall facing, and requiring only the forming of a simple or plain opening in the wall facing in order to accommodate the mounting or the case carried thereby. In accordance with the present invention the opening required in the wall facing need be only a simple aperture that accommodates the case, and the structure of the present invention is such that it in no way mars, pierces or mutilates the wall facing in which the opening is provided.

Another object of this invention is to provide a casing mounting of the general character referred to which requires no application of screws or like fasteners to the wall or to the wall facing.

A further object of the invention is to provide a case mounting of the character referred to that can be applied easily and quickly and without

2

the use of special tools or equipment, and without the exercise of special skill or care.

A further object of the invention is to provide a casing mounting of the general character referred to involving clamp means engaging the wall facing, and which serves to support or mount the casing so that it is securely and rigidly held stationary relative to the wall.

It is another object of this invention to provide 10 a casing mounting of the general character referred to that is exceedingly simple in form and construction and is inexpensive of manufacture, making the structure commercially practical.

The invention in a typical case is applied to a 15 wall facing in which a suitable opening has been cut and it serves to mount a case in the opening. The case may be a sheet metal unit of box-like form having flat side walls and a bottom. In a situation where the case is the body of a lighting fixture there may be a closure provided to

20 fit over the open front of the case, and in such a situation the closure can be suitably connected, as, for instance, linked to the case. The present invention provides one or more units or clamp

25 means on or in connection with the case and engageable with the casing of the wall. Where the case is box-like it is preferred to employ two clamp means on opposite sides of the case, and these means may correspond in form and construction.

30 A typical clamp means embodying the invention involves two jaws, one an inside jaw and the other an outside jaw, and means connecting the jaws together and to the wall of the case. The jaws may be similar in that each may

35 involve an elongate body in the form of a strip or band of sheet metal, and it may involve one or more teeth or grippers projecting from one longitudinal edge of the body. In a typical situation it is advantageous that the inside jaw have

40 a plurality of spaced grippers, whereas the outside jaw can be advantageously formed with but one gripper. Openings, preferably slots, are provided in the wall of a case to pass the grippers of the inside jaw, and in a typical situation when

45 the case has been inserted in the opening in the wall facing the inside jaw is applied so its body bears against the inside of the case wall, while the grippers of the jaw project through the slots in the wall to overlie the inside of the wall facing.

50 The outside jaw has its body applied over the body of the inside jaw with its gripper or grippers projecting to overlie the outside of the wall facing. The connecting means serves to connect the jaws against movement relative to each other and to connect the jaws to the wall

of the case so that the structure can be set with the parts firmly established in fixed relationship with the grippers of the inside and outside jaws clamped to the facing of the wall so that that part of the wall is held tightly between the grippers. In a typical situation the connecting means involves one or more projections on the wall of the case and openings in the bodies of the jaws. In a typical case the openings in the body of the inside jaw are simple round holes, whereas those in the body of the outside jaw have portions that will pass or receive the projections, and elongated portions or slots which cooperate with the projections to establish the desired gripping engagement between the jaws and the facing of the wall. In a preferred construction the last mentioned portions of the openings in the body of the outside jaw may be elongate or slot-like openings, pitched or angularly related to the longitudinal axis of the jaw so that this jaw can be shifted lengthwise, with resulting cam or wedge action that causes effective clamping of the wall facing between the grippers of the jaws. In a preferred construction the projections on the wall of the case are screws and when the structure has been set or operated to establish the desired gripping of the wall facing, the projections can be operated, for instance tightened, to thereby clamp and, in effect, lock the structure in the clamping position. In one form of the invention an operating means may be provided, for instance, a screw means, serving to operate the outside jaw so that its body moves lengthwise to gain the desired cam or clamp action above referred to.

The various objects and features of my invention will be fully understood from the following detailed description of typical preferred forms and applications of the invention, throughout which description reference is made to the accompanying drawings, in which:

Fig. 1 is a sectional view of a typical lighting fixture embodying the present invention, showing it in working or engaged position with the facing of a wall. Fig. 2 is a sectional view of the structure shown in Fig. 1, being a view taken as indicated by line 2-2 on Fig. 1. Fig. 3 is a view taken at one of the side walls of the fixture case, showing this part free of other elements of the structure and showing a typical slot construction employed in carrying out the invention. Fig. 4 is a view taken as indicated by line 4-4 on Fig. 1, showing the closure of the fixture in an open position. Fig. 5 is a detailed sectional view through a wall facing with a fixture case abutting the facing at the point where the casing is to be mounted and showing a marking device being employed to mark the facing with a line to indicate the point at which the wall facing must be cut to provide an opening for the case. Fig. 6 is a sectional view of an apertured wall facing showing a wall of the fixture case after the case has been inserted in the opening in the facing preliminary to the clamp means being installed. Fig. 7 is a view similar to Fig. 6, showing the inside clamp jaw applied or installed. Fig. 8 is a view similar to Fig. 7 showing the outside clamp jaw applied and a projection on the case holding the clamp jaws engaged together and with the wall of the case. Fig. 9 is a perspective view of the inside clamp jaw showing it free of the other portions of the structure. Fig. 10 is a perspective view of the outside clamp jaw showing it free of the other portions of the structure. Fig. 11

is a view similar to a portion of Fig. 4, showing another form of construction, and Fig. 12 is an enlarged sectional view of a portion of Fig. 11, being a view taken as indicated by line 12-12 on Fig. 11.

As indicated above, the present invention, in practice, can be employed to mount various elements on or in connection with a wall, and it can be used to advantage to mount a housing, casing, or other such construction. For purpose of example, the invention is here shown and will be described in detail as mounting the case of a lighting fixture and certain aspects of the invention are specifically set forth in connection with a light fixture of the recessed type wherein there is a closure that cooperates with the mounting of the present invention and the casing of the fixture that is held by the structure of the present invention.

In the drawings a typical building wall W is shown as having a facing A and the facing is indicated as involving lath or plasterboard 10 at its inner portion and a layer of plaster 11 at its outer portion. The inner side 12 of the facing 20 is shown plain and smooth, whereas the outer side 13 of the plaster 11 is shown plain and smooth and, in practice, is ordinarily finished for instance, coated as by means of paper or plaster.

The particular lighting fixture illustrated in the drawings involves, generally, a housing or case B, illuminating means C in the case, a closure D for the case, and coupling means E connecting the closure and case.

The case B of this type of lighting fixture, that is, of the recessed type of fixture such as is shown in the drawings, may vary widely in size and form and, for example, the one illustrated in the drawings is of simple and typical form. The particular case B illustrated involves side walls 20 and a back 22 which elements cooperate to form a forwardly opening box-like structure. In practice it is common to form such parts of sheet metal, and as shown in the drawings the several parts of the case may be simple, flat, or plain sheet metal plates, and the side walls 20 may be joined together at their ends by suitable connections, and the back 22 can be joined to the rear edges of the side walls by any suitable means or construction. The particular case illustrated in the drawings is of the type adapted to be inserted in an opening 25 provided in a wall facing A, so that the outer edges 26 of the side walls of the case are substantially flush with or just within the outer face 13 of the facing A. In the particular form of fixture illustrated the case B of the fixture has four side walls 20 establishing a casing rectangular in form, as clearly illustrated in Figs. 1 and 2 of the drawings. It is to be understood, however, that fixtures of the general character referred to vary in form and may be various types of polygonal structures, or may even be round, as circumstances require. It is to be understood that as the fixture case varies, the present invention may be modified or varied accordingly, so that the principles of the invention are suitably carried out.

The illuminating means illustrated in the drawings involves a reflector 30 in the case and it is shown as including a suitable socket 31 carrying a globe 32. The socket 31 is shown supported on a suitable mounting bracket 33 in the desired position relative to a fitting 34 carried by one wall 20 of the case, which fitting carries

or cooperates with a flexible duct 35 provided to carry wires 36.

The closure D provided in the case illustrated involves a rectangular frame 40 which may be formed of metal or the like, and a panel 41 of suitable material such as glass or the like carried by the frame. The frame is shown as somewhat larger than the open end of the case B and its peripheral portion is shaped, for instance, inwardly turned, so that there are marginal lips 42 of the frame that engage the outer face 13 of the wall facing A, as clearly illustrated in Fig. 1 of the drawings.

The coupling means E illustrated in the drawings connect the closure D with the case B so that the closure can be readily operated between the positions shown in Figs. 1 and 4 of the drawings. The means E involves, generally, a pair of arms 45 pivotally carried by the case and pivotally connected to a suitable flange 46 in the frame 40. Springs 47 are related to the arms and are such as to normally yieldingly hold the arms in the position shown in Fig. 1, where the closure is in the desired operating position. The present invention is in no way concerned with this feature or detail of the fixture and the means E shown in the drawings is merely a typical structure of this kind and is of the particular construction disclosed and claimed in the application of Samuel L. Beber and Jerome H. Feig, filed August 17, 1950, bearing Serial No. 180,004, entitled "Lighting Fixture."

The present invention provides one or more units or clamp means serving to mount the case B in the desired manner in connection with the wall facing A. In a typical case where a light fixture is being mounted two units of the present invention can be employed to advantage, and in such case these are alike and are applied to walls 20 of the case B that are opposite each other, as is shown in the drawings.

The clamp means, or each unit of the clamp means, embodying the present invention involves, generally, an inner or inside jaw 50, an outer or outside jaw 51, and means 52 connecting the jaws together and to the wall of the case.

The inside jaw 50 of the clamp means is carried by the wall 20 of the case, preferably at the inner side thereof, and it has one or more grippers that project from the outer side of the wall 20 and are so located as to engage or bear against the inner side or surface 12 of the wall facing A. In the particular construction illustrated the jaw 50 involves an elongate strip or band of suitable material, such as sheet metal, forming a body 55, and one or more grippers 56 is carried by the body. In the particular case illustrated two grippers 56 are carried by the body 55 and are spaced apart lengthwise of the body so that there is a gripper extending to or adjacent each end of the body. The grippers 56 are flat flange-like projections on the innermost edge 57 of the body 55, and they are in a plane normal to that of the body 55, so that the body is L-shaped in cross-sectional configuration, as will appear from Figs. 7 and 9 of the drawings.

The body 55 of the jaw 50, being an elongate flat sheet metal part, is adapted to be arranged at the inner side 58 of wall 20, and in a typical arrangement of parts it may be arranged against or adjacent the side 58 of wall 20, as shown in Fig. 7 of the drawings. The body 55 is preferably made of such size, for instance, of such width, that when it is in operating position at the inner side of wall 20 its outer edge 59 is substantially flush with the

outer edge 26 of the case. In accordance with the invention one or more openings 60 is provided in the wall 20 to pass or accommodate the gripper or grippers 56 of the jaw 50. It is preferred, in practice, that the openings 60 be elongate or slot-like in form, and they are so located in wall 20 as to occur immediately inside of the inside face of the wall 12 of the facing A, as is clearly shown in Fig. 6 of the drawings. Where the jaw 50 has two grippers 56, as shown in Fig. 9, there are two slot-like openings 60 in the wall 20 and these are of such size, both as to width and length, as to suitably pass or accommodate the grippers 56, as shown in Fig. 7 of the drawings. By providing spaced grippers on the jaw 50 there may be spaced openings 60 in the wall 20 so that the provision of the openings does not materially weaken or impair the desired structural characteristics of the case. Furthermore, it is desirable that the openings 60 be made only large enough to suitably pass the grippers so that there are no undesirable openings in the case when the structure is in operation. When the inside jaw 50 is in operating position, as shown in Fig. 7, the grippers 56 of that jaw project from the outer side of wall 20 and are in position to engage or bear against the inner face or side 12 of facing A.

The outside jaw 51 may, in practice, be similar, generally, to the jaw just described, for instance, it may have an elongate body 61 and one or more grippers 62 projecting from the body. In the case illustrated there is a single gripper 62 projecting from body 61, and it projects from the outer edge 63 of the body. The gripper 62 is preferably a flat flange-like projection on the body in a plane normal to that of the body, so that the jaw 51 is substantially L-shaped in cross-sectional configuration, as clearly shown in Fig. 10 of the drawings.

In a typical arrangement of parts the jaw 62 of body 61 is engaged with or over the body 55 of jaw 50, and the gripper 62 of jaw 51 extends over the edges 26 and 59 of wall 20 and jaw 50, respectively, to overlap and engage the outer surface 13 of facing A of the wall W.

The connecting means 52 serves to connect the jaws 50 and 51 together and to the wall 20 of the case, and in practice may involve one or more light units or units of construction serving this purpose. In the case illustrated two units of connecting means are provided in connection with the related jaws 50 and 51, and are spaced apart lengthwise of the jaws. Each such unit of the means 52 preferably involves a projection on or carried by the wall 20 so that it projects from the inner side 58 of the wall 20 and the bodies of the jaws have openings that accommodate or cooperate with that projection. In accordance with the broader principles of the invention the projection of means 52 may vary widely in form and construction. However, in practice it is advantageous to establish the projection as a screw, in which case a suitable screw has a shank 70 threaded to or through the wall 20 and has a head 71 on the inner end of the shank and spaced from the inner side 58 of wall 20. When the jaw 50 is employed so that its body 55 is adjacent the wall 50, this body 55 may be provided with a simple aperture in the form of a round opening 72 of such size as to freely pass the shank 70 of the projection on wall 20. The opening in the body 61 of jaw 51 may be somewhat more complex or may be of special form, and in the case illustrated in Figs. 1 to 10 of the drawings the opening in body 61 of jaw 51 is a bayonet type opening or slot having a shank passing portion 75 and an

inner shank holding portion 76. The shank passing portion 75 is shown open at or entering the body from the inner edge 77 of the body 61, and it extends laterally of the body to a point about midway between the edges 77 and 63 of the body. The portion 76 of the openings in body 61 is an elongate slot continuing from the portion 75 in a direction generally lengthwise of the body. This portion 76 of the opening is preferably pitched or inclined relative to the longitudinal axis of jaw 61 in a manner such as is shown in Fig. 10 of the drawings.

With the construction above described the outside jaw 51 can be applied by manipulating it so that the portion 75 of the opening passes the shank of the screw projection on wall 20, allowing the jaw to pass or be entered between the head 71 of the screw and the body 55 of jaw 60.

When the shank is opposite, or in register with the end of the open portion 76 that joins the portion 75, body 55 is in position so that it can be moved lengthwise with consequent wedging or wedge action, which causes the gripper 62 of jaw 51 to move toward the grippers 56 of jaw 50. This action is continued until the grippers are both in tight or suitable gripping engagement with the facing A of the wall W. In practice, it is desirable that the incline or pitch of the portion 76 be slight, so that when the jaw 51 is once suitably pressed into operating position the parts will remain in that position until deliberately operated in a manner to release the structure. If desired, the structure can be set or locked after the jaws have been engaged, as by tightening the screw projections of the means 52. By employing screws to form the projections above described these elements of the structure serve not only as part of the means holding or cooperating with the jaws but they also serve as a setting or locking means that can be operated to make the construction secure against any possible release or failure.

In the form of the invention illustrated in Figs. 11 and 12, the construction as a whole may be identical with that hereinabove described, except that the opening or openings provided in the body 61^a of jaw 51^a are slightly different in form from those above described. The projection receiving portions 75^a of the openings in body 61^a are simply large, round openings, sufficiently large to accommodate or pass the heads 71 of the projections of the wall 20. The portions 76^a of the openings extend from the openings 75^a and are elongate, inclined openings having wedge action, the same as the openings 76 above described. In this form of the invention screw means is illustrated which can, if desired, be used in connection with the structure first described. The screw means, as illustrated, involves a single set screw 80 in an ear 81 projecting from the body 61^a of jaw 51^a. The screw 80 is disposed to extend parallel with the body 61^a and the ear which carries the screw is so located that the screw bears against a wall 20 of the case adjacent the wall carrying the clamp jaws, and the head 82 of the screw 80 is located so that it can be easily or conveniently engaged by a screw driver or the like. From Figs. 11 and 12 it will be apparent how the screw 80 can be operated to shift the clamp jaw 51^a longitudinally and thus cause effective camming or wedge action, setting the clamp construction so that the facing of the wall W is effectively gripped. The screw 80 not only serves to thus shift or operate the jaw 51^a of the clamp means, but when the structure has been once set through this action the screw 80 serves as a re-

tainer or set screw holding the clamp means set or engaged until such time as the screw 80 is deliberately operated to release the structure.

It is to be observed that the gripper 62 of outside jaw 51 is such as to overhang or overlap the facing A of wall W adjacent the opening 25, providing an effective grip, whereas when the closure D is in position, as shown in Fig. 1, the gripper 62 is within or beneath a lip 42 of frame 40 and is thus concealed.

It is to be noted that the gripping device or means provided by the present invention, as hereinabove described, enables the case B of the fixture to be handled freely, without the jaws 50 and 51 being connected to the case. Furthermore, it is to be observed that the case B may have its open end portion formed as shown in the drawings, so that it is plain and wholly without flanges, lips, ears, or other protuberances. Under such circumstances when a fixture is to be applied to a wall, as for instance to a ceiling portion of a wall, the case can be applied to the facing A at the point where the fixture is desired, and a marking device such as a pencil P can be employed to draw a line around the case after the fashion illustrated in Fig. 5 of the drawings. If the wall is then cut along the line thus scribed, the desired opening 25 is provided in the facing A, and if reasonable care is employed in cutting this opening the case A will slidably fit into the opening in a manner such as is shown throughout the drawings.

From the foregoing description it will be apparent that in the mounting of a casing employing the present invention, after the opening 25 has been formed in facing A, the case B of the fixture can first be connected with a flexible duct 35 of suitable length, and can then be moved into the wall through the opening 25 until the case is related to the facing A, as shown in Fig. 6, or it can even be moved somewhat inward beyond this position. The inside jaw 50 can then be arranged or inserted as shown in Fig. 8, whereupon the outside jaw 51 can be installed, which operation can be performed either before or after the screw projections are applied to the wall 20, as by being passed through the openings 72, and into suitable openings 90 provided in the wall 20. When the clamp jaws have been suitably set, as hereinabove described, either by simple manual shifting, or by operation of a set screw such as the screw 80, the structure can, if desired, be locked by setting of the screw projections that hold the jaws to the walls 20.

It is to be noted that with the construction provided by the present invention a case such as the case of a fixture or a case designed to have any suitable function, can be applied to an element such as the facing of a wall, by merely cutting a suitable opening in that facing. The structure of the invention provides for clamping of the structure in place, and requires application of no screws, nails, or other elements to the facing A that might cause chipping, damage or mutilation thereof. Furthermore, it is to be observed that the application of the structure of the present invention to a facing A requires no pounding, jarring, or forcing such as is likely to chip, crack, or injure plaster, but rather, involves simple clamping action, and the structure is such that if desired the clamp construction can be released, freeing the case from the facing A, making possible removal whenever desired.

Having described only typical preferred forms and applications of my invention, I do not wish

to be limited or restricted to the specific details herein set forth, but wish to reserve to myself any variations or modifications that may appear to those skilled in the art and fall within the scope of the following claims:

Having described my invention, I claim:

1. In combination, a case having a wall with an opening, two relatively movable jaws having overlying bodies inside the case and adjacent the wall and having spaced opposed grippers projecting from the bodies and from the outside of said wall, a gripper of one jaw being passed by said opening, the bodies of the jaws having registering openings therein, and a projection on the wall projecting inward therefrom and engaged in the openings in the bodies of the jaws connecting the bodies together and to the wall, the opening in one jaw being a cam slot.

2. In combination, a case having a wall with an aperture therethrough and spaced from an edge of the wall, two relatively movable elongate jaws having bodies inside said wall and having spaced opposed grippers projecting from the bodies and from the outside of said wall, the body of one jaw being engaged against the inner side of the wall and a gripper thereon being engaged through the aperture and located thereby in a predetermined position relative to said edge, the body of the other jaw being engaged over and against that of the first mentioned jaw and a gripper thereon projecting past the wall to be opposite and spaced from the first mentioned gripper and outward from said edge, and a projection on the wall engaged through openings in the bodies of the jaws connecting the bodies and holding them relative to the wall, the opening in the body of said other jaw being a cam slot extending longitudinally of said other jaw to effect shifting of the gripper thereof relative to said edge.

3. In combination, a case having a wall with an outer edge and with an aperture therethrough spaced from the edge, two relatively movable jaws having elongate bodies inside said wall and having spaced opposed grippers projecting from the bodies and from the outside of said wall, the body of one jaw being engaged against the inner side of the wall and a gripper thereon being engaged through the aperture, the body of the other jaw being engaged over and against that of the first mentioned jaw and a gripper thereon projecting past said edge of the wall to be opposite and spaced from the first mentioned gripper, and a screw threaded to the wall and engaged through openings in the bodies of the jaws connecting the bodies and holding them relative to the wall, the opening in the body of said other jaw being a cam slot inclined longitudinally of that body whereby the body of said other jaw can be shifted longitudinally to vary spacing of the gripper thereon relative to the said edge.

4. In combination, a case having a wall with an exposed edge and with an elongate aperture therethrough spaced from and parallel with said edge, two relatively movable jaws having bodies inside said wall and having spaced opposed elongate grippers projecting from the bodies and from the outside of said wall, the body of one jaw being engaged with the inner side of the wall and a gripper thereon being engaged through the aperture and guided thereby parallel with said edge, the body of the other jaw being engaged over that of the first mentioned jaw and a gripper thereon projecting past the wall to be opposite and spaced from the first mentioned

gripper, and a screw carried by the wall and engaged through openings in the bodies of the jaws connecting the bodies and holding them relative to the wall, the opening in the body of said other jaw being an elongate aperture removed from the margins of the body and inclined lengthwise of the body.

5. In combination, a case having a wall with an exposed edge and with an aperture therethrough spaced from the edge, two relatively movable jaws having elongate bodies inside said wall and having spaced opposed grippers projecting from the bodies parallel therewith and projects from the outside of said wall, the body of one jaw being engaged with the inner side of the wall and a gripper thereon being engaged through the aperture, the body of the other jaw being engaged over that of the first mentioned jaw and a gripper thereon projecting past the wall to the opposite and spaced from the first mentioned gripper, and a projection on the wall engaged through openings in the bodies of the jaws connecting the bodies and holding them relative to the wall, the opening in the body of said other jaw being a slot with angularly related portions, one of which opens at an edge of the body.

6. In combination, a case having a wall with an exposed edge and with an aperture therethrough, spaced from said edge, two relatively movable jaws having bodies inside said wall and having spaced opposed grippers projecting from the bodies and from the outside of said wall, the body of one jaw being engaged with the inner side of the wall and a gripper thereon being engaged through the aperture, the body of the other jaw being engaged over that of the first mentioned jaw and a gripper thereon projecting past the wall to be opposite and spaced from the first mentioned gripper, and a clamp screw carried by the wall and engaged through openings in the bodies of the jaws connecting the bodies and holding them relative to the wall, the screw having a head inside the case, the opening in the body of said other jaw being a slot with angularly related portions, one of which opens at an edge of the body, the gripper on the last mentioned body projecting from an edge thereof opposite to that at which the slot opens.

7. In combination, a case having a wall with an aperture therethrough, two relatively movable jaws having bodies inside said wall and having spaced opposed grippers projecting from the bodies and from the outside of said wall, the body of one jaw being engaged with the inner side of the wall and a gripper thereon being engaged through the aperture, the body of the other jaw being engaged over that of the first mentioned jaw and a gripper thereon projecting past the wall to be opposite and spaced from the first mentioned gripper, a projection on the wall engaged through openings in the bodies of the jaws connecting the bodies and holding them relative to the wall, the opening in the body of said other jaw being a cam slot, and means operable to shift the body of said other jaw relative to the projection.

8. In combination, a case having a wall with an aperture therethrough, two relatively movable jaws having bodies inside said wall and having spaced opposed grippers projecting from the bodies and from the outside of said wall, the body of one jaw being engaged with the inner side of the wall and a gripper thereon being engaged through the aperture, the body of the

other jaw being engaged over that of the first mentioned jaw and a gripper thereon projecting past the wall to be opposite and spaced from the first mentioned gripper, a projection on the wall engaged through openings in the bodies of the jaws connecting the bodies and holding them relative to the wall, the opening in the body of said other jaw being a cam slot, and a screw operable to shift the body of said other jaw relative to the projection.

9. In combination, a case having an end portion that is open and having a side wall a part of which is at said open end portion of the case and has an opening therein, two relatively movable jaws separate from the case and having overlapping bodies inside said wall and having spaced opposed grippers projecting from the bodies and from the outside of said wall, a gripper of one jaw extending through said opening in the side wall, and means releasably connecting the overlapping bodies of the jaws together and to the inside face of said side wall and including a manually operable part inside the case.

10. In combination, a case with an end portion that is open, the case having a side wall with an outer edge at the open portion of the case and having an elongate opening spaced inward of said edge and extending parallel therewith, two relatively movable jaws separate from the case and having overlapping bodies inside the case and adjacent the inside face of said wall and having elongate substantially parallel grippers projecting from the bodies, one gripper extending through the opening in the side wall and one extending over said edge establishing spaced opposed relatively movable grippers extending out from said side wall, and means releasably con-

necting the jaws together and to said side wall and operable from the interior of the case.

11. In combination, a case with an end portion that is open, the case having a side wall with an outer edge at the open portion of the case and with a slot spaced inward of and parallel with said edge, two relatively movable jaws adapted to shift relative to the case and having overlapping bodies in the case adjacent the inner side of said side wall and having grippers projecting from the bodies at substantially right angles thereto, the body of one jaw being engaged against the inner side of the side wall and a gripper on said body extending through the slot while the body of the other jaw is engaged over and against that of the first mentioned jaw and has a gripper thereon engaged over said edge of the side wall, the grippers being opposed and projecting at the outer side of the side wall, and screw means connecting the jaws together and to said side wall including an operating head exposed at the inside of the case.
